CAN PUNCHER

Filed Jan. 23, 1928

INVENTOR.

GEORGE W. DRUHE.

BY
Harry C. Schroeder
ATTORNEY

UNITED STATES PATENT OFFICE

GEORGE WALTER DRUHE, OF PIEDMONT, CALIFORNIA

CAN PUNCHER

Application filed January 23, 1928. Serial No. 248,623.

My invention relates to a device for punching holes in cans, and is particularly adapted for use in connection with condensed milk cans or the like wherein it is necessary to 5 punch holes in the top surface of said cans in order that the contents may be poured therefrom.

An object of my invention is to provide a 10 punching device for a can, in which a plurality of holes may be punched in the top thereof and be equi-distant from the side wall of the can.

Another object of my invention is to provide a punching device for a can in which the 15 holes punched by said device will be spaced from the rim of said can at a distance determined to allow the most efficient pouring of the contents thereof.

A further object of the invention is to provide 20 a device of the character indicated, which can be readily made of sheet metal stampings and which at the same time is light and strong.

A still further object of this invention is 25 to provide a device for punching cans which is highly useful and simple in construction. Convenience of arrangement, lightness and comparative inexpensive of manufacture are further objects which have been borne in 30 mind in the production and development of this invention.

With these and many other objects in view, which will more readily appear as the nature 35 of the invention is better understood, the same consists in parts which will hereinafter be more fully described, illustrated and claimed.

In the accompanying drawings

Figure 1 is a side elevation of the preferred 40 embodiment of my device shown in operative relation with respect to a can.

Figure 2 is a perspective view of the preferred embodiment of my device.

In manufacturing this device it is extremely important that the device will be 45 simple in construction so that the expense of production will be negligible, as the device is particularly designed so that it may be given to a customer upon the purchase of a certain brand of condensed milk, or the like.

The device itself may have the product man-

ufacturer's trademark printed thereon. As will be clearly seen, the device will stimulate the sales of a product and also serve as an excellent advertising medium, the comparatively small cost of manufacture being offset 55 by its advertising value.

Referring to the accompanying drawings wherein similar reference characters designate similar parts throughout, the various figures described above adequately illustrate 60 my invention, and the following detailed description is commensurate with the above mentioned drawings in enabling an artisan to construct the same.

The reference numeral 1 designates the 65 punching device in its entirety. The device is preferably made from a narrow strip of sheet metal forming a handle 2, one end of said strip is provided with a pair of spaced projections 3 and 4. The space between the 70 projections 3 and 4 may be of any suitable width but it is preferable that said space be comparatively narrow for the purpose to be hereinafter set forth.

The other end of the strip 2 is bent as 75 at 5 so as to form a handle for the device, said bent portions of said strip being secured together by means of suitable rivets 6, thereby forming a light and strong handle 80 for the device.

The projection 3 of the device is provided with a sharpened end 7 substantially as shown in the drawings, said projection forming a punch. The projection 4 functions as a spacer for positioning the punch 7 with relation to the side wall of the can and for this reason it is of greater length than the projection 3 and extends beyond the end thereof.

Figure 1 shows my invention in operative 90 relation with respect to a conventional type of can designated by the numeral 8. Preparatory to the punching of a hole in the can 8, the device is held in upright position on the top surface 9 of the can 8, the sharpened end 7 of the projection 3 engaging said surface. The sharpened edge 7 is spaced from the rim 10 of the can 8 by means of the space between projections 3 and 4. As the projection 4 is longer than the projection 3, as 100

heretofore described, said projection will engage the side wall of the can 8 in a sliding action, as is clearly shown in Figure 1. The space between the projections 3 and 4 will determine the distance between the hole punched by the puncher 7, and the side wall of the can. It is preferable that said space be comparatively small so that the hole punched will be close to the side wall of the can so as to facilitate the pouring of the contents from said can.

I am aware that some changes may be made in the general arrangement and combinations of the several devices and parts, as well as in the details of the construction thereof without departing from the scope of the present invention as set forth in the foregoing specification and as defined in the following claim; hence, I do not limit my invention to the exact arrangements and combinations of the said device and parts as described in the said specification, nor do I confine myself to the exact details of the construction of the said parts as illustrated in the accompanying drawings.

Having thus described my invention, what I now claim as novel and desire to secure by Letters Patent, is:

A can head punch comprising a flat strip of metal bent upon itself forming a loop-like handle at one end, spaced apart tynes formed at the other end thereof, one of the said tynes forming a punch and the other of said tynes functioning as a spacer.

In testimony whereof I affix my signature.

GEORGE W. DRUHE.
